(57) **CLAIM**

The ornamental design for an electric coffee grinder as shown and described.

DESCRIPTION

FIG. 1 is a front, right and top perspective view of a first embodiment of an electric coffee grinder, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of a second embodiment of an electric coffee grinder.

FIG. 10 is a rear, left and bottom perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan elevation view thereof, and,

FIG. 16 is a bottom plan elevation view thereof.

The dashed broken lines depict portions of the electric coffee grinder that form no part of the claimed design.
